ATTORNEYS.

UNITED STATES PATENT OFFICE.

ABRAM V. S. HICKS, OF ROCKVILLE CENTRE, NEW YORK.

COMBINED HAMMOCK AND SUPPORTING-FRAME.

SPECIFICATION forming part of Letters Patent No. 223,588, dated January 13, 1880.

Application filed October 11, 1879.

To all whom it may concern:

Be it known that I, ABRAM V. S. HICKS, of Rockville Centre, in the county of Queens and State of New York, have invented a new and Improved Combined Hammock and Supporting-Frame; and I do hereby declare that the following is a full, clear, and exact description of the same.

My invention is an improvement in the class 10 of beds formed of a folding frame and a hammock attached thereto.

The invention consists in the peculiar construction and arrangement of parts, as herein-after described and claimed.

15 In accompanying drawings, forming part of this specification, Figure 1 is a side view of my improved folding bed—to wit, hammock and frame extended in position for use. Fig. 2 is a side view of a portion of a frame, showing a different arrangement of certain parts. Fig. 3 is a plan view of one end of the hammock and supporting-frame. Fig. 4 is a side view of the frame folded.

20 A is a netting constituting the body of the hammock or bed proper, and firmly attached at its ends to the stretcher-bars B by means of lacing a. C C are staying and tightening cords, which are rove through the side meshes of the netting A, and attached to the ends of 25 bars B by a timber-hitch, and made fast to the cross-bars b b of the folding bed-frame, which suspends and supports the hammock when extended, as shown in Fig. 1.

25 The ropes C C are of especial use in supporting and strengthening the sides of the hammock A, so that there will be little danger of the occupant falling out, and yet the ropes may be easily taken up or let out, for the purpose of changing the tension of the netting A, as required.

30 The same ropes C being extended beyond the stretchers B, no separate ropes or attaching devices are requisite for suspending the hammock, and hence the danger of the latter becoming detached and the occupant injured by a fall is reduced to a minimum.

35 The mode of attaching the netting A to the end bars and the extension of ropes C adapts the hammock A B C for attachment to hooks 40 or various fixed objects when it is desired to use it independently of the folding frame.

The frame consists of the pairs of bars E, which are jointed together at their inner ends, and connected by rounds e e', and of the

45 pairs of tension-bars F connected by rounds b 55 and d.

The jointed bars E constitute the main portion or body of the frame. They are divided in the middle of their length and connected by hinges e, in order to adapt the frame to be 60 folded in small space, as shown in Fig. 4.

For the purpose of strengthening the joints e by increasing the surfaces in contact, I cut the inner ends of the bars E obliquely, so that the latter are at a slight angle to each other 65 when the frame is extended, as shown in Fig. 1.

The necessity for separate devices for strengthening the joints e is thereby avoided, and the thickness of the bars A need be only 70 the same as if they were integral or made in one piece.

The tension-frame F is pivoted between the bars E on the rounds c of the latter, as shown in Figs. 1, 3, 4. Hooks G are attached to ends of the bars E for holding bars F elevated and the 75 netting A distended; but in Fig. 2 the hooks are attached to the ends of bars F and connect with staples attached to bars E at points between the pivot-rounds c and hinges e.

By the latter construction the bars E may 80 be made shorter, since they do not require to project beyond the pivot c of bars F, as when the hooks are attached, as shown in Figs. 1, 3, 4.

In either construction, the tension-bars F 85 project below the bars E, and such extensions form legs that support the hammock or bed-frame on the floor or ground.

I do not claim, broadly, a folding bed-frame having its longitudinal portion formed in two 90 parts, hinged together so as to adapt them to fold compactly.

What I claim is—

The combination of the netting and the bars E E of the folding bed-frame with bars F, 95 acting as tension-bars and supporting-legs, which bars F are connected in pairs and pivoted to said bars E, so as to extend downward below the same when in use, but made of such length as to fold compactly with the body of 100 the frame when not in use, as shown and described.

The above specification of my invention signed by me this 7th day of October, 1879.

A. V. S. HICKS.
